GOLF CLUB

Leonard A. Young, Detroit, Mich.

Application June 17, 1933, Serial No. 676,291

11 Claims. (Cl. 273—77)

In the manufacture of golf club heads such as drivers, brassies and spoons, wood has been the material commonly used and found most satisfactory. However, great care must be exercised in the selection of the material and choice of materials from which wood golf club heads may be manufactured is very restricted. Further, there is a decided tendency toward warping and checking.

10 The main objects of this invention are:

First, to provide a golf club head structure in which the main body is of wood so reinforced and supported throughout that the tendency or likelihood of splitting or warping and checking 15 under varying conditions of use is substantially eliminated.

Second, to provide an improved golf club head having these advantages which may be very economically produced.

20 Third, to provide a golf club head which is very distinctive and attractive in appearance.

Fourth, to provide a golf club head in which the tendency of the stroke to be deflected when contacting with the ground is minimized, and 25 one in which the club is encouraged to follow through after contact with the ground.

Objects pertaining to details and economies of the invention will definitely appear from the description to follow. The invention is defined in 30 the claims.

A structure embodying the features of my invention is clearly illustrated in the accompanying drawing, in which:

Fig. 1 is a front perspective view of a golf club 35 embodying my invention, a portion of the shaft being broken away.

Fig. 2 is a fragmentary bottom perspective view.

Fig. 3 is a transverse section on line 3—3 of 40 Figs. 2 and 4.

Fig. 4 is a fragmentary longitudinal section on line 4—4 of Fig. 3.

Fig. 5 is a transverse section of a modified form or embodiment of my invention.

45 Fig. 6 is a fragmentary transverse section of another modification or embodiment of my invention.

In the embodiment of my invention illustrated in the accompanying drawing the head 1, formed 50 of wood, is provided with an integral hosel 2 to which the shaft 3 is attached. The head is suitably conformed and provided with a face having the desired loft, depending on whether the club is to be used as a driver, brassie or spoon.

In the top of the head I form a plurality of spaced parallel longitudinal slots or kerfs 4 having rounded bottoms 5 as indicated by dotted lines in Fig. 4. In the bottom of the head I provide a plurality of spaced longitudinal parallel slots or kerfs 6 disposed in alternating relation and overlapping within the body as shown in Figs. 3 and 4. The bottoms 7 of the kerfs 6 are also curved and these kerfs or slots may be effectively formed by a multiple saw.

10 Each top kerf has a plate 8 fitted and secured therein, and each bottom kerf has a plate 9 likewise fitted and secured therein as by means of suitable glue so that the plates in effect become an integral part of the structure. The 15 plates are preferably formed of aluminum and their outer edges are flush with and conformed to the surface of the head. When formed of aluminum the head may be machined with the ordinary tools employed for that purpose, that is, the plates are roughly conformed to the head and the finishing work on the head may be done as though the plates were not present.

The bottom of the head, including the plates, has a transverse groove 10 receiving the sole 25 plate 11. This sole plate 11 has a flange-like impact portion 12 disposed in a recess 13 in the striking face of the head. The sole plate is preferably longitudinally curved transversely of the head as best shown in Fig. 3, the edges 30 also being curved as shown in Fig. 4. This provides a guiding shoe for the club which is particularly desirable in a driver so that, in the event of the club striking the ground, the sole plate tends to maintain the direction of stroke 35 of the head or the club is encouraged to follow through after striking the ground.

In the modification shown in Fig. 6 the sole plate 14 is flat as is usual practice in golf clubs. In the embodiment shown in Fig. 6 the bottom 40 reinforcing plates 9 are ornamented. In the embodiment shown in Fig. 5 the top reinforcing plates 8 are ornamented, also the sole plate as is sometimes the practice.

The head 15 shown in Fig. 5 is provided with 45 an impact or striking plate 16.

With the parts thus arranged great care in wood selection is not required. At the same time the club is very attractive and distinctive in appearance, is very strong, and not likely to 50 warp or check. With suitable glue the reinforcing plates are secured within the head so that, in effect, they become an integral part thereof, as stated.

I have not attempted to illustrate various 55

other modifications or adaptations which may be desired for particular club designs, as it is believed that this disclosure will enable those skilled in the art to embody or adapt my improvements as may be best suited to the particular design.

Having thus described my invention what I claim as new and desire to secure by Letters Patent is:

10. 1. A golf club head comprising a wood body having a recessed impact face and a plurality of spaced parallel longitudinal kerfs in the top thereof and a plurality of spaced parallel longitudinal kerfs in the bottom thereof, the top and bottom kerfs being disposed in alternating relation and overlapping in spaced relation within the body, the latter being continuous in a wave-like path transversely of said kerfs, and flat plates fitting and fixedly secured within said kerfs, the outer edges of said plates being conformed to and flush with the surface of the head and the ends and inner edges thereof terminating within the body of the club head.
15. 2. A golf club head comprising a fibrous body having a face and a plurality of spaced kerfs in the top and bottom thereof arranged parallel to the vertical axis of the club and having curved bottoms and ends terminating within the body so that the latter is continuous at its ends, the body being also continuous in a wave-like path extending transversely of the face, and a metal plate fitting within each kerf to reinforce the head against splitting, warping, checking and the like.
20. 3. A golf club head comprising a wood body having a plurality of spaced parallel longitudinal kerfs in the top thereof and a plurality of spaced parallel longitudinal kerfs in the bottom thereof, the top and bottom kerfs being disposed in alternating relation and overlapping within the body, flat plates fitting and fixedly secured within said kerfs, the outer edges of said plates being conformed to and flush with the surface of the head, and a sole plate disposed transversely below the bottom plates.
25. 4. A golf club head comprising an integral body having a plurality of spaced kerfs in opposite surfaces thereof arranged in parallel relation and terminating within the body to provide continuity in the body in a wave-like path extending above, between and below the kerfs, and a reinforcing plate filling each of said kerfs.
30. 5. A golf club head of integral fibrous material having a rounded top and a plurality of spaced parallel thin kerfs in the top and bottom of the head, said kerfs being spaced from the ends and opposite sides of the head so that the head retains its integrality, and reinforcing plates tightly fitting within said kerfs with their exposed surfaces conformed to the surface of the head, the plates acting to prevent the head from warping, splitting, checking and the like.
35. 6. A golf club head comprising a wood body having a plurality of spaced parallel longitudinal kerfs in the top thereof and a plurality of spaced parallel longitudinal kerfs in the bottom thereof, the top and bottom kerfs being disposed in alternating relation and overlapping within the body, and flat aluminum plates fitting and fixedly secured within said kerfs, the outer edges of said plates being conformed to and flush with the surface of the head.
40. 7. A golf club head comprising a fibrous body having a plurality of spaced kerfs in the top and bottom of the head, said kerfs being spaced from the ends and opposite sides of the head so that the head retains its integrality, and reinforcing plates tightly fitting within said kerfs with their exposed surfaces conformed to the surface of the head, the plates acting to prevent the head from warping, splitting, checking and the like.
45. 8. A golf club head of integral fibrous material having a plurality of spaced parallel thin kerfs in the top of the head, said kerfs being spaced from the ends and opposite sides of the head so that the head retains its integrality, and reinforcing plates tightly fitting within said kerfs with their exposed surfaces conformed to the surface of the head, the plates acting to prevent the head from warping, splitting, checking and the like.
50. 9. A golf club head of integral fibrous material having a plurality of spaced parallel thin kerfs in the bottom of the head, said kerfs being spaced from the ends and opposite sides of the head so that the head retains its integrality, and reinforcing plates tightly fitting within said kerfs with their exposed surfaces conformed to the surface of the head, the plates acting to prevent the head from warping, splitting, checking and the like.
55. 10. A golf club head of integral fibrous material having a plurality of spaced parallel thin kerfs in the bottom of the head, said kerfs being spaced from the ends and opposite sides of the head so that the head retains its integrality, and reinforcing plates tightly fitting within said kerfs with their exposed surfaces conformed to the surface of the head, the plates acting to prevent the head from warping, splitting, checking and the like.
60. 11. A golf club head of integral fibrous material having a plurality of spaced parallel thin kerfs in the bottom of the head, said kerfs being spaced from the ends and opposite sides of the head so that the head retains its integrality, and reinforcing plates tightly fitting within said kerfs with their exposed surfaces conformed to the surface of the head, the plates acting to prevent the head from warping, splitting, checking and the like.
